his Attorney*

UNITED STATES PATENT OFFICE.

FREDERICK G. ROEDELL, OF DUBUQUE, IOWA, ASSIGNOR OF ONE-HALF TO ROBERT P. ROEDELL, OF DUBUQUE, IOWA.

APPARATUS FOR SOFTENING AND DIFFUSING LIGHT.

Application filed November 17, 1922. Serial No. 601,503.

To all whom it may concern:

Be it known that I, FREDERICK G. ROEDELL, a citizen of the United States of America, residing at Dubuque, in the county of Dubuque and State of Iowa, have invented certain new and useful Improvements in Apparatus for Softening and Diffusing Light, of which the following is a specification.

10 My invention relates to improvements in automobile headlights, in the means for softening and diffusing light, and in the construction of light screens.

An object of my invention is an improved 15 means for eliminating part of the violet rays of a strong, artificial light and of producing by diffusion a soft and efficient light that has no glare, spot-light effect or other objectionable features. A further object is 20 to construct a light screen which is particularly adapted to be used on the front of vehicle lights such as automobile headlights. A further object of my invention is the use of a translucent material between 25 two panes of glass, or other suitable material, this translucent material being coated with oil and crumpled in such a manner that the oil is retained on the surface of the translucent material to receive and modify 30 the rays of light.

With these and further objects in view, one embodiment of my invention is shown in the accompanying drawings in which:—

Figure 1 is a front elevation of my improved lens attached to a conventional automobile head light casing;

Figure 2 is a vertical section through the lens and casing therefor; and

Figure 3 is an enlarged fragment of the 40 section shown in Figure 2.

My lens may be placed in any suitable frame, and it is understood that my invention is not limited by the fact that it is disclosed in the drawings as it may be 45 used in an automobile head light. It is evident it may be used as an art window or in any other place where it is desired to have the light diffused in the manner it is diffused by my invention.

50 A frame 1 is made of two pieces of suitable material, one piece 2 having an extension at one edge thereof which is bent

around the part 3 on the other piece constituting the frame. These two pieces may be clamped together as indicated at 4. Intermediate the edges of the two pieces they are brought together or depressed forming a groove 5. The depressed parts may be attached as by rivet 6, producing a hollow frame 7 which by reason of its construction 55 is a strong resilient frame. The edges adjacent the clamped together parts of the frame constitute spring clamps or fingers 8. It will be evident that my screen may be 60 efficiently and satisfactorily clamped between these two fingers.

The screen is constructed of two panes or pieces of suitable glass 9 and 10, or other suitable material, between which are placed one or more sheets of gelatin, two sheets 70 11 and 12 being shown which have been thoroughly crumpled or otherwise brought to an uneven and an irregular surface. These sheets of gelatin or of other material having similar qualities are coated 75 with an oil such as a clear mineral oil or with a liquid having qualities similar to oil, and then placed between the glass or other plates. A thin filament and globules of oil 13 are formed over the entire surface 80 of the gelatin. The crumpling of the sheet results in the formation of many prism effects through which the light is refracted. The oil and gelatin are hermetically sealed by constructing the glass or other panes 85 with shoulders 14 or by any other satisfactory means and by filling the space between the shoulders with a cement 15. The glass or other panes forming the screen may have a bead on the outer edge thereof 90 if desired to facilitate fastening the screen to the frame.

It is evident that rays of light are diffused by passing through the sheets of translucent, crumpled material. It has been 95 found by experiment that the crumpling of the oiled sheets of gelatin segregates a great number of globules of oil which act as miniature lenses filtering and diffusing the light which passes through them. The 100 effect of the translucent material, oil and glass, or other suitable material, is to break up the violet rays, giving the light the desired effect and at the same time taking

away the glare and spot-light effects which are objectionable in head lights and some other lights.

My invention is adapted to be used to produce any desired color effects by the use of the proper colors for the material forming the screen.

Having described my invention, what I claim and desire to protect by Letters

10 Patent is:—

1. In a device for diffusing and softening artificial light, the combination of a transparent medium and a translucent medium, said translucent medium holding on the 15 surface thereof an oil filament and globules of oil.

2. In a light screen, media through which the light passes comprising a transparent medium and a translucent medium, said 20 translucent medium consisting of a sheet

of gelatin having the surface thereof rendered uneven and irregular and having the surface thereof covered with oil.

3. In a light screen, media through which the light passes comprising a transparent 25 medium and a translucent medium, said translucent medium consisting of a crumpled sheet of gelatin having on the surface thereof globules of oil and an oil filament.

4. In a light screen, media through which the light passes comprising a transparent medium and a translucent medium, said translucent medium consisting of a sheet of 35 gelatin having the surface thereof rendered prismatic in effect and having the surface thereof covered with oil.

In testimony whereof I affix my signature.

FREDERICK G. ROEDELL.
